FIG. 1

FIG. 2

FIG. 3

FIG. 5

FIG. 4

FIG. 6

FIG. 7

FIG. 1 is a front perspective view of a support for a hanging flower pot or the like showing my new design, the rear being the same as the front shown;

FIG. 2 is a vertical cross sectional view of FIG. 1;

FIG. 3 is a fragmentary cross sectional view of a modified form of the support for a hanging flower pot or the like shown in FIG. 1;

FIG. 4 is a fragmentary cross sectional view of a second modified form of the support for a hanging flower pot or the like shown in FIG. 1;

FIG. 5 is a fragmentary cross sectional view of a third modified form of the support for a hanging flower pot or the like shown in FIG. 1;

FIG. 6 is a front perspective view of a fourth modified form of the support for a hanging flower pot or the like shown in FIG. 1, the rear being the same as the front shown; and

FIG. 7 is a fragmentary cross sectional view of FIG. 6.

The broken line representation of an attaching screw in FIG. 1 is for purposes of illustration only.

I claim:

The ornamental design for a support for a hanging flower pot or the like, substantially as shown and described.
